UNITED STATES PATENT OFFICE.

GEORGE E. HEIDBREDER, OF QUINCY, ILLINOIS.

COOKING RANGE OR STOVE.

1,330,187.

Specification of Letters Patent. Patented Feb. 10, 1920.

Application filed May 28, 1919. Serial No. 300,252.

To all whom it may concern:

Be it known that I, GEORGE E. HEIDBREDER, a citizen of the United States, residing at Quincy, in the county of Adams, 5 State of Illinois, have invented a new and useful Cooking Range or Stove; and I do hereby declare the following to be a full, clear, and exact description of the invention, such as will enable others skilled in 10 the art to which it appertains to make and use the same.

The invention relates to cooking ranges or stoves and has for its object to locate the fire box, oven and flues so that the width of 15 the stove may be reduced to a minimum, thereby providing a stove wherein the dimensions of the fire box, oven and flues may be of the same size and dimensions as the present ranges now in use, and providing a structure which may be easily shifted 20 from a coal to a gas range.

A further object is to provide a stove wherein the heat from the fire box is carried by flues, which flues encircle the oven 25 and the heat passes rearwardly after encircling the oven into the chimney or stove pipe, at a point above the oven and substantially centrally thereof.

A further object of the invention is to 30 provide an oven for a stove, said oven having a flue extending around the same, said flue terminating at a point above the oven and discharging into the chimney flue, and a damper so disposed that the heat from 35 the fire box may be allowed to pass around the oven or directly into the chimney flue.

With the above and other objects in view the invention resides in the combination and arrangement of parts as hereinafter 40 set forth shown in the drawings, described and claimed, it being understood that changes in the precise embodiment of the invention may be made within the scope of what is claimed without departing from 45 the spirit of the invention.

In the drawings:—

Figure 1 is a vertical longitudinal sectional view through the stove and oven.

Fig. 2 is a sectional view taken on line

50 2—2 of Fig. 1.

Referring to the drawings, the numeral 1 designates the body of the stove, which comprises the end walls 2 and side walls 3. The body 1 rests upon a suitable base 4, 55 said body 1 being provided with a bottom

5, thereby forming a rectangular chamber. One of the walls 2 is provided with a depression 6, in which depression a water tank 7 is disposed. A top 8 is disposed on the top of the body 1, which top may be 60 provided with any number of openings for the reception of cooking utensils, or if so desired, a gas burner tray may be disposed on the top by eliminating the top 8.

An oven 9 is provided, said oven being 65 formed by the walls 10, 11, 12 and 13, the walls 13 extending upwardly thereby forming an oven with an apex 14, which apex 14 is substantially centrally disposed with relation to the oven. The oven walls are 70 spaced from the walls 2 of the side of the body member and the bottom 5, thereby forming flues 15, 16 and 17. A wall 18 is provided, thereby forming a flue 19 and 20, said flues 15, 16, 17, 19 and 20 forming a 75 flue extending completely around the oven and terminating substantially at a central point above said oven. The wall 18 is provided with an upwardly extending wall 21, the upper end of which extends slightly inwardly and terminates in the horizontal portion 22, said horizontal portion being provided with a downwardly curved wall 23, which wall 23 is provided with an opening 24, the wall 23 has its lower end secured 80 or otherwise engaging the apex 14 of the oven 9. A damper 26 is pivoted on the wall 23 and is adapted to be thrown in and out of engagement with said wall, thereby opening and closing the opening 24, said 85 damper 26 being so positioned that when it is in open position it will engage the wall 2 as at 27, thereby preventing the passage of heat around the oven and compelling the heat to pass through the opening 24 into the flue 90 opening 28 at the rear of the stove, however during this positioning of the damper for direct draft it will be seen that the heat as it passes from the fire box 29 will come in contact with the wall of the tank 7, thereby 95 heating the water no matter whether damper is positioned for direct draft or not.

A chamber 30 is formed between the walls 18 and 2, which chamber may be utilized 100 as an ash pit if so desired, an ash pan 31 being represented as disposed below said chamber. A clean-out opening 32 is provided in the rear wall of the body member 1, said opening being in communication 110

with the flue 17 thereby providing means whereby access to the flue may be gained for cleaning the same.

When it is desired to use the oven for baking or other purposes the heat leaves the fire box 29 and passes through the passages or flues 33, 34, 15, 16, 17, 19 and 20, following the directions of the full line arrows *a* and passing through the flue opening 28 to the chimney. By the positioning of the flue opening 28 above the top of the oven it will be seen that a complete circuit is completed around the oven walls, and at the same time the heat will come in contact with the top cover of the stove for its entire width, thereby allowing the utilization of the same for cooking as well as baking, also that the heat will come in contact with the water tank 7.

When the damper 26 is moved to the dotted line position 35 as shown in Fig. 1 the heat from the fire box 29 will follow the directions of the dotted line arrows *b*. During its course under these conditions the heat will also come in contact with the under surface of the stove top for its entire length, and also will contact with one of the walls of the tank 7, then be deflected by the damper 26 through the opening 24, and thence through the flue opening 28, which is called a direct draft. It will be seen that the oven will be uniformly heated and that what heat is lost toward the end of the flues around the oven will be compensated for by the location of the fire box, from which heat will be radiated through the walls 18.

The invention having been set forth what is claimed as new and useful is:—

1. A cooking range or stove comprising an oven, said oven having upwardly inclined walls forming an apiced top, walls spaced from the walls forming the oven thereby forming a flue around said oven of substantially the same contour as the oven, one of said spaced walls having an upwardly and

inwardly inclined wall terminating in a horizontal wall, said horizontal wall terminating in a downwardly extending wall, the lower end of which engages the apex 50 of the oven, a damper controlled opening in said downwardly extending wall, a fire box located above the apex of the oven and to one side thereof, a discharge flue located between the upwardly and inwardly extending wall and the downwardly extending damper wall, and means whereby said damper may be moved so that the heat may either be forced to pass around the oven or deflected through the damper controlled 60 opening and into the discharge flue opening as desired.

2. A cooking range or stove comprising an oven, walls spaced from the walls forming the oven, thereby forming a flue around 65 said oven of substantially the same contour as the oven, one of said spaced walls having an upwardly and horizontally extending wall forming the inner side of the fire box, the horizontal wall terminating at a 70 point substantially above the center of the oven, said end of the horizontal wall being provided with a downwardly extending wall, the lower end of which engages the top wall of the oven, a damper controlled opening in 75 said downwardly extending wall, a fire box located adjacent the upwardly and horizontally extending wall, a discharge flue located between the upwardly and horizontally extending wall and the downwardly extending damper wall, and means whereby said 80 damper may be moved for forcing the heat to pass around the oven to the discharge flue or direct to said discharge flue at a point above the oven.

In testimony whereof I have signed my name to this specification in the presence of two subscribing witnesses.

GEORGE E. HEIDBREDER.
